US00D742676S

(12) **United States Design Patent** (10) **Patent No.:** **US D742,676 S**
Smith et al. (45) **Date of Patent:** **** Nov. 10, 2015**

(54) **CHAIR**

(71) Applicant: **Steelcase Inc.**, Grand Rapids, MI (US)

(72) Inventors: **Bruce M. Smith**, East Grand Rapids, MI (US); **Glen Oliver Löw**, Hamburg (DE); **James N. Ludwig**, East Grand Rapids, MI (US); **Robert J. Battey**, Middleville, MI (US); **Gordon J. Peterson**, Rockford, MI (US); **Russell T. Holdredge**, Alto, MI (US); **Todd D. Krupiczewicz**, Alto, MI (US); **Nathan R. Brock**, Alto, MI (US)

(73) Assignee: **Steelcase Inc.**, Grand Rapids, MI (US)

(**) Term: **14 Years**

(21) Appl. No.: **29/518,043**

(22) Filed: **Feb. 19, 2015**

Related U.S. Application Data

(63) Continuation of application No. 14/029,141, filed on Sep. 17, 2013, now Pat. No. 9,027,998, which is a continuation of application No. 29/432,767, filed on Sep. 20, 2012, now Pat. No. Des. 697,727.

(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.

The broken lines shown in the drawings are for illustrative purposes only and form no part of the claimed design.

1 Claim, 7 Drawing Sheets
